ATTORNEY

UNITED STATES PATENT OFFICE.

JOSEPHINE L. HOLT, OF PORTLAND, OREGON.

ABDOMINAL SUPPORTER.

1,379,101.

Specification of Letters Patent. Patented May 24, 1921.

Application filed October 28, 1917. Serial No. 198,884.

To all whom it may concern:

Be it known that I, JOSEPHINE L. HOLT, a citizen of the United States, residing at Portland, in the county of Multnomah and 5 State of Oregon, have invented certain new and useful Improvements in Abdominal Supporters, of which the following is a specification.

This invention relates to abdominal supporters.

The object of the invention is to so construct a device of this character that it may be detachably applied at will to maternity belts, surgical corsets, and abdominal 15 reducers.

Another object is to so construct a device of this character that while it is very simple and cheap to manufacture is thoroughly efficient for the purpose for which it is intended.

20 With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

30 In the accompanying drawings:—

Figure 1 represents a side elevation of this improved supporter shown applied,

Fig. 2 is a similar view taken from the side opposite to that shown in Fig. 1,

35 Fig. 3 is a rear elevation of the abdominal supporting band detached,

Fig. 4 is a detail front elevation showing the connection between one end of the band and its connector,

40 Fig. 5 is a detail longitudinal section.

In the embodiment illustrated in Figs. 1 to 5 the device constituting this invention is shown applied to a maternity belt and comprises an abdomen supporting band 1,

45 which is preferably composed of a longitudinally yieldable transversely non-yieldable fabric strip curved throughout its length and also throughout its width to form a cupped band adapted to conform to the

50 shape of a protruding abdomen and provided at its upper and lower edges with reinforcements 2 which are also longitudinally yieldable when the band is made of yieldable fabric. By constructing this band in

55 the manner above set forth, that is, to cause it to yield longitudinally but not trans-

versely, it is designed to fit and hold within bounds a protruding abdomen, so that it will not project and present an unsightly appearance, and yet the longitudinal expansion of the band will provide for the comfort of the wearer. This band 1 tapers toward its ends which are equipped with transversely extending reinforcing strips 3 and 4 secured thereto by stitching as shown at 5, 60 the strip 3 being wider than strip 4 and made of two-ply inelastic material, between the plies of which the end of the band 1 is positioned and secured by stitching. Longitudinal casings 6 extend transversely of the 70 band and are formed in strip 3 by spaced rows of stitches which may be used to receive stiffeners, not shown. Longitudinally alined and spaced eyelets 7 are formed in strip 3 to receive a lacing cord 8 whereby the end of the band 1 may be adjustably connected with 75 an attaching device shown in the form of a casing 9 having a stiffener therein and which is designed to be connected with a back supporting member or connector 9', the latter 80 being of any desired construction.

The strip 4 at the other end of band 1 is also constructed of two-ply material with the band end inserted between the plies and stitched. This strip 4 carries fastening elements here shown in the form of eyes 10 which are designed to be detachably engaged with hooks 11 carried by an attaching device 9'' in the form of a casing similar to casing 9, used at the opposite side of the 90 band.

The attaching members 9 and 9'' are designed to be secured to the back member 9' of a belt as shown in Figs. 1 and 2 by stitching, lacing or otherwise, and are preferably 95 provided with lacing eyelets 12 through which cords may be passed for lacing the members 9 and 9'' to the corset, belt or reducer in connection with which this support is designed to be used.

100 Hose supporters 13 are shown depending from the lower edge of the band 1 and are provided with the usual connecting devices for uniting them to the hose to be supported as shown at 14. Similar hose supporters 105 15 are carried by the lower ends of the members 9 and 9'' and operate to support the hose and also to hold the supporter in adjusted position.

110 From the foregoing description, taken in connection with the accompanying drawings, the advantages of the construction and of

the method of operation will be readily apparent to those skilled in the art to which the invention appertains and while I have described the principle of operation of the 5 invention together with the device which I now consider to be the best embodiment thereof, I desire to have it understood that the device shown is merely illustrative and that such changes may be made as are within the 10 scope of the claimed invention.

I claim:—

As a new article of manufacture an abdomen supporter comprising an abdomen supporting band curved throughout its 15 length and also throughout its width to conform to the shape of the wearer's abdomen, said supporting band being longitudinally yieldable and having its upper and lower edges provided with reinforcing strips also 20 longitudinally yieldable, a transversely extending vertical reinforcing non-elastic strip secured to each end of said supporting band,

and extending from top to bottom thereof, a connector shaped to conform to the contour of the back of the wearer and being 25 of substantially twice the width of said supporting band and provided with transversely extending vertical reinforcing non-elastic bands at the respective ends thereof, said ends being of substantially twice the width 30 of the band ends and extending from top to bottom of the connector, a series of lacings connecting said supporting bands to said connector to project above the upper end of the supporting band, and means for 35 detachably connecting the opposite end of the supporting band to said connector.

In testimony whereof I affix my signature in presence of two witnesses.

JOSEPHINE L. HOLT.
